UNITED STATES PATENT OFFICE.

ELLEN F. QUINN, OF CORONA, NEW YORK.

REVERSIBLE HEEL.

1,400,182.

Specification of Letters Patent. Patented Dec. 13, 1921.

Application filed December 22, 1919. Serial No. 346,493.

To all whom it may concern:

Be it known that I, ELLEN F. QUINN, a citizen of the United States, residing at Corona, Long Island, in the county of 5 Queens and State of New York, have invented certain new and useful Improvements in Reversible Heels; and I do declare the following to be a full, clear, and exact description of the invention, such as will enable 10 others skilled in the art to which it appertains to make and use the same.

This invention relates to improvements in heels for boots and shoes, more particularly to revoluble or adjustable heels.

15 The primary object is to provide a simple and practical means for easily attaching a heel to a boot or shoe.

Another object is to provide a heel, which, when attached to a shoe, may be easily adjusted without loosening screws or other 20 similar fastening elements.

With the above and other objects in view, the invention consists of certain novel features of construction and of the combination 25 and arrangement of parts as will be more fully described and claimed.

I attain these objects by constructing the heel and fastening means, as illustrated in the accompanying drawings, in which—

30 Figure 1 is a side elevation of the heel portion of a shoe having the removable heel connected therewith.

Fig. 2 is a vertical sectional view of the heel and fastener.

35 Fig. 3 is a bottom plan view of the improved heel, the fastener being indicated by dotted lines.

Similar reference numerals designate similar parts throughout the several views.

40 Reference is now had to the drawings in which is shown a shoe having the usual sole S, upon which is secured a heel bed plate 1. A circular revoluble heel 2 formed of leather, rubber or other suitable material is 45 provided.

A flat metal ring 4 is secured to the heel 2 by any suitable fasteners such as nails. The metal at the inner edge of the ring is offset upwardly to form a continuous flange 5, which is substantially L-shaped in cross-

50 section. The heel is revolubly secured to

to the shoe or the bed plate 1, by providing a flat metal disk 6 which is provided with a boss 8 fitting into the socket and internally threaded to receive the screw 9 which is inserted from within the shoe. The bed plate is grooved or channeled to receive the ring, so that said heel 2 and plate 1 will snugly contact one another. The forward edge of the heel is protected by attaching to the shoe 60 a curved block 10 of leather or the like material as shown in Fig. 3.

With heels of this character it is seen that after a portion of the edge has been worn, the heel may be revolved to position a new 65 unworn edge in place of the worn one. This operation may be readily performed without loosening the screw or nails, as is ordinarily necessary.

From the foregoing description taken in 70 connection with the accompanying drawing, the construction and operation of the invention will be readily understood without requiring a more extended explanation.

Various changes in the form, proportion 75 and minor details of construction may be resorted to without departing from the principle or sacrificing any of the advantages of the claimed invention.

I claim:

A reversible heel comprising a permanent heel portion having a socket cut from its lower face and having a recess in its lower face forming a seat positioned about and in spaced relation to the socket, a ring 85 positioned in the seat about the socket, a disk fitting against the portion of the permanent heel portion inclosed by the ring and extending in overlapping relation to the ring, the portion of the permanent heel 90 portion inclosed by the ring engaging the inner face of the disk, a boss extending from the plate into the socket and having a threaded opening, a heel fitting beneath the permanent heel portion and having the ring 95 connected with its upper face, and a securing screw extending through the permanent heel portion and into the threaded opening of the boss.

In testimony whereof I have hereunto 100 set my hand.

ELLEN F. QUINN.
